UNITED STATES PATENT OFFICE.

HERMANN LEMP AND OTTO F. PERSSON, OF LYNN, MASSACHUSETTS, AS
SIGNORS TO ELIHU THOMSON, OF SWAMPSCOTT, MASSACHUSETTS.

CONTROLLING MECHANISM FOR AUTOMOBILES.

SPECIFICATION forming part of Letters Patent No. 729,776, dated June 2, 1903.

Application filed January 30, 1901. Serial No. 45,333. (No model.)

To all whom it may concern:

Be it known that we, HERMANN LEMP and OTTO F. PERSSON, citizens of the United States, residing at Lynn, county of Essex, State of Massachusetts, have invented certain new and useful Improvements in Controlling Mechanism for Automobiles, of which the following is a specification.

The present invention relates to the steering and speed-controlling devices for automobiles, and has for its object to improve their construction and to provide an apparatus which is simple in construction and reliable in operation.

In the accompanying drawings, attached to and forming a part of this specification, we have illustrated an embodiment of our invention, in which—

Figure 1 is a plan view of a vehicle. Fig. 2 is a plan view of the means employed for varying the cut-off and also of the means for controlling the admission of steam to the engines. Fig. 3 is a detail plan view of the mechanism employed for shifting the cut-off cams. Fig. 4 is a vertical section taken through the center of the controlling-stand, certain of the parts being in elevation. Fig. 5 is a plan view of the controlling-stand and operating-handles, and Fig. 6 is a plan view of the eccentric employed to operate the throttle-valve.

Referring to Fig. 1, A represents the body of the vehicle, which is supported by suitable springs A' from the axles of the vehicle. Inside the body are the necessary fuel and water tanks, together with the boiler and burner. These have not been shown, because any of the well-known structures may be employed. Located beneath the body of the vehicle or in any suitable place are two engines B and B', (indicated in dotted lines.) The engines, as shown, are of the three-cylinder single-acting type but other forms of engines may be employed if desired. Each engine is directly connected with one of the driving-wheels by the sprocket-chain C. The engines are entirely separate, and are therefore capable of independent operation. This arrangement we have found to be extremely satisfactory, since if an accident happens to one engine or to the power-transmitting

mechanism between the engine and its driving-wheel the engine can be cut out of service by means hereinafter described. If for any reason it is found desirable, the sprocket-chain 55 may be removed from the disabled engine, so as not to interfere in any way with the operation of the other engine. We have found that by providing a suitable check or locking device for the steering-wheels no inconvenience is 60 experienced in running the vehicle with one engine, the check taking care of any tendency which might exist for the vehicle to move out of its normal path. By this arrangement we are also enabled to dispense with differential 65 gearing between the driving-wheels, as the engines can run at the required different speeds while the carriage is rounding curves. The front axle is stationary, and mounted on the ends thereof are hangers D, in which are 70 pivotally supported the short bell-crank axles D'. This arrangement forms a part of the well-known double-axle suspension. On the front axle or other fixed support is a steering-check E, so arranged that the transmission 75 of wheel strains to the operating or steering handle is prevented, as shown in the patent to Hermann Lemp, No. 692,868, issued February 11, 1902. The rearwardly-extending 80 arms of the bell-crank levers or short axles are connected by the rods D'. Secured to the moving part of the steering-check is a frame E', and the rods D' are pivotally secured thereto. Extending laterally from the operating-shaft E' of the locking device is an arm F, 85 which arm is united with a corresponding arm F' on the end of the steering-lever by a rod F'. Situated above the frame E' and extending between the spring-pressed buffers E' is an actuator E'. It is by means of this 90 actuator that motion is transmitted from the steering-tube or shaft E' to the wheels. The first movement of the handle in the direction to steer first compresses the spring of one of the buffers, releases the lock, and then moves 95 the steering-wheel, if one is used, or both wheels, as in the present instance.

We have found by experience that it is desirable to be able to steer the vehicle from either the right or left hand side, and to accomplish this we provide a steering-handle G, which is pivotally secured to the con-

trolling-stand. This handle may either be used in the position shown or swung to the opposite side, so that the person sitting in the right-hand seat can control the vehicle.

5 It will be noticed that the handle G is very close to the seat. This brings it within easy reach of the operator, and it is necessary to raise it from the position shown in order that the operator may get out of his seat. The 10 arrangement shown has been found to be a satisfactory one, but its position may be altered as desired to meet the conditions of service.

Between the steering - handle G and the 15 throttle-lever H we have provided an interlock, the mechanism of which will be more fully described hereinafter. The object of this interlock is to prevent the removal of the throttle-valve except in specified instances— 20 that is to say, when the steering-handle G is appreciably moved from the horizontal position which it normally occupies.

The engines receive steam from a common supply-pipe I, Figs. 1 and 4, and are controlled by a single throttle-valve I. In addition to this each pipe leading from the throttle to an engine is provided with a cut-out valve J, the object of this last-mentioned valve being to render one or the other of the engines 30 inoperative, and ordinarily it would only be used when trouble existed with the engine or with the power-transmitting mechanism.

Referring to Fig. 4, the construction of the controlling-stand will be described. A² represents the floor of the vehicle, and A³ the vertically - extending board, located underneath the seat. Situated above the floor of the vehicle is a guide and support A⁴, which is secured to any suitable part of the vehicle- 40 body. The tube is free to move vertically in this guide for the purpose of adjustment. Located at the union of the floor-piece A² with the vertically-extending board A³ is an angle-iron A⁵, which forms a part of the vehicle-frame, and rigidly secured thereto is a socket A⁶. Mounted in this socket is the main tube or support L, which is stationary and constitutes the controller-stand. By arranging the parts so that they are all supported from the same point the strains between them are reduced to a minimum and the parts will always be in proper alinement. Mounted for rotary movement within this stand are two tubes. The outer tube is connected to the mechanism for shifting the cut-off and reversing mechanism of the engines, and the inner tube is connected to the steering mechanism through the lever F', Fig. 1. Mounted for rotary movement within the 60 steering-tube M is a shaft N, which controls the throttle that regulates the admission of steam to the engines.

The means for operating the cut-off mechanism will now be described. To the upper 65 end of the cut-off-actuating tube O is secured a handle O' of any suitable construction. In the present instance it is shown as being an

ordinary hand-wheel. To the lower end of the tube is secured a pinion O², Fig. 3, which meshes with the segmental spur-gear O³. The latter is mounted on a shaft O⁴, that is secured to the under side of the socket A⁶, and consequently bears at all times a fixed relation with the other operating parts. The segmental gear O³ is provided with a second set 70 of teeth, the pitch-diameter of which is less than that of the first set. This second set of gear-teeth is lettered O⁵ and meshes with rack-teeth P, which teeth are formed on a sleeve that is rigidly secured to the sliding 75 piece P'. The back of the sleeve P is provided with a series of notches, with which the antifriction-roller carried by the outer end of the arm P² is adapted to engage, a spring P³ being employed to force the roller into the 80 notches. The object of this arrangement is to insure the speed-controlling mechanism being set at certain definite positions. Referring to Fig. 3, the parts are so arranged that when the roller on the end of arm P² is 85 in the position shown the cut-off mechanism is set in a manner to produce backward rotation of the engine or engines. When the roller is in the second notch, the parts are in the "stop" or "off" position. The next 90 notch gives the first speed forward, and the second or last notch gives the high-speed position of the cut-off mechanism. It is of course understood that the speed variations are also controlled by the throttle-valve. If desired, 95 the cut-off mechanism may be reversed, so that what is now the backward-running position will be the high-speed forward-running position. The slide P' is mounted in guides P⁴, which are formed integrally with the socket A⁶. 100 One of the guides is extended to form a support for the pivoted roller-carrying arm P². The ends of the slide are extended at right angles to the normal plane of movement, as at P⁵, and these extensions are adjustably 105 connected to the shafts Q, which change the position of the cut-off. The particular type of cut-off valve has not been illustrated, since it may be of any well-known construction. The outer ends of the rods Q are screw-threaded, and the extensions P⁵ are clamped 110 between the nuts Q'. The cut-off-mechanism-actuating tube passes down through the socket A⁶ and is guided thereby. The upper end of the tube is secured to the hand-wheel 115 O', having an elongated hub, a portion of which hub extends between the stationary outer tube and the actuating-tube. This serves as a bearing for the upper end, and the pinion O² and the shoulder on the hand-wheel will prevent endwise movement of the 120 two tubes.

Referring now to the steering mechanism, M represents the steering-tube, which in the present controller-stand is the inner tube. 130 This has been found to be a satisfactory arrangement, although it may be departed from without changing the spirit of our invention. The essential feature of this portion of our

invention is to provide a self-contained controlling-stand, which is preferably centrally located, with concentrically-arranged parts, each part being maintained in definite relation with the others. On the lower end of the tube is mounted an arm F', which is pivotally connected to the rod F², as indicated in Fig. 1. Rigidly secured to the upper end of this tube is a support M', comprising a split collar, which surrounds the sleeve and is clamped in place by a retaining-bolt. Extending laterally from the collar is a projection or stud M². Pivotally mounted on this stud and retained in place by a screw M³ is a steering-handle G. Between the steering and cut-off-actuating sleeves is a bearing M⁴, which is retained in place by the same bolt that clamps the handle O' to the tube O. Between the upper surface of the hub of the handle and the split collar M' is a sleeve. The lower end of the tube has a bearing in and is centered by the pinion O², and this, together with the parts mentioned above, holds the tubes in alinement and prevents independent endwise movement. The handle and the throttle H are interlocked. In the present instance the interlock is shown as consisting in part of an arm G', having a hook or projection formed on its outer end. This hook or projection is screw-threaded to the handle and is arranged to engage with the circular flange H' formed on the socket or head of the throttle-lever H. In order that the steering-handle may be used either on the right or on the left hand side of the vehicle, two of these arms G' are provided, one being operative when the steering-handle is used on the left-hand side, the other being operative when the steering-handle is used on the right-hand side. In the position shown the throttle-lever cannot be removed, because the flange H' formed therein will engage the projection on the end of the arm G'. In order to remove the throttle, it is necessary to raise the steering-handle G to a point where the projection on the arm G' will clear the flange. In the structure shown it is necessary to raise the handle somewhat more than forty-five degrees, although this can be varied as desired. In order to prevent tampering with the vehicle, it is desirable to have the throttle-lever removable, so that when the operator leaves the vehicle the lever may be taken off. By providing the interlock all danger of the lever being inadvertently removed while the vehicle is in operation is prevented.

The admission of steam to the engines is controlled by the shaft N, which is provided at its upper end with an enlargement or hub N', that fits into the steering-tube M, and is capable of moving independently thereof. The upper end of this enlargement is provided with a head of irregular shape, which fits into a correspondingly-shaped socket in the throttle-lever H. The lower end of the shaft N is provided with an eccentric R, Figs. 4 and 6, which eccentric is provided with a hub which

enters the lower end of the steering-tube M and makes a working fit with the arm F', secured to the bottom thereof. The shaft N is rigidly secured to the hub of the eccentric, and the latter is provided with a collar, and this collar, together with the enlargement N' at the upper end of the shaft N, holds the throttle mechanism against vertical movement. The reduced portion of the enlargement N' and the extension-hub of the eccentric R guide the throttle mechanism in its rotary movement. Surrounding a concentric portion or hub of the eccentric is a support S, and the latter is connected to the casing of the throttle-valve I by means of two rods S'. In the particular instance shown the rods are secured to the casing by means of straps S², which surround the projections on the valve-casing, both being employed to hold the parts in place. With an arrangement of this kind a certain freedom of movement is permitted between the eccentric and the throttle-valve to compensate for strains to which the vehicle is subjected. Surrounding the eccentric is an eccentric-strap T, Figs. 4 and 6, which is connected to the throttle-valve stem by a link connection T'. The arrangement of the throttle-handle H with the throttle-valve is such that a movement through one hundred and eighty degrees will move the throttle-valve from off to full on position. Secured to the casing of the throttle-valve I are pipes J', Figs. 1 and 4, which pipes are connected with the valves J for cutting the engines out of service. Each valve J is provided with a stem J², having a rectangular head which is adapted to be fitted into a socket formed in the operating-handle. Since these valves are not commonly used, no handle is permanently attached to the valve-stem.

It will be seen that the controlling and steering mechanisms are arranged in a most convenient manner, at the same time being very compact and presenting a neat appearance. By arranging the several mechanisms in a single stand we are enabled to avoid the use of independent levers located at separate points, which use is always objectionable.

A stand of the character above described is self-contained—that is to say, the structure as a whole is supported from one point, and the bearings between the tubes being carried by the tubes themselves there is no chance of the parts getting out of alinement.

In accordance with the provisions of the patent statutes we have described the principle of operation of our invention, together with the apparatus which we now consider to represent the best embodiment thereof; but we desire to have it understood that the apparatus shown is only illustrative and that the invention can be carried out in other ways.

What we claim as new, and desire to secure by Letters Patent of the United States, is—

1. In a vehicle, the combination of a motor, a tubular support, a motor-controlling device, a handle for actuating the device, a tube

mounted within the support and connected to the controlling device, a handle attached to the tube for moving it, a steering-wheel, a tube concentrically mounted within the support, 5 a rod and lever for connecting the wheel to the last-mentioned tube, a handle normally extending across the vehicle for moving the wheel, and a pivot for the last-named handle which is supported by the tube and extends 10 transversely to the plane of movement of the handle so that the latter can be thrown upward to facilitate entering and leaving the vehicle.

2. In a vehicle, the combination of a body, 15 a stationary tube that acts as a support, a socket arranged to carry the tube, a motor, a reversing mechanism, means for attaching the reversing mechanism to the socket, and a guide for the upper end of the stationary tube 20 which is attached to the body.

3. As an article of manufacture, a self-contained controlling-stand for vehicles, comprising a tubular support, a holder therefor, a steering-tube, a handle that is pivotally 25 connected to the steering-tube and is capable of being used on the right or left-hand side, a tube for actuating the cut-off, a means for actuating a throttle, and bearings between the several tubes and the throttle-actuating 30 means which are supported by the tubular support.

4. As an article of manufacture, a controlling-stand for vehicles, comprising a tubular support, a socket in which said support is located, a tube mounted for movement within the support, bearings for the tube, a second tube mounted within the first and capable of movement independent thereof, bearings for the second tube, an actuator mounted within 40 the second tube, bearings therefor, and a handle for moving one of the tubes the hub of which engages with the support for preventing independent vertical movement of the actuator.

45 5. In a controlling-stand, the combination of a support, an actuator mounted therein, variable cut-off mechanism, gearing between the actuator and the cut-off mechanism, and a spring-pressed roller for adjusting the cut-off 50 mechanism to certain definite positions.

6. In a controlling mechanism, the combination of a variable cut-off mechanism, a rack for moving the cut-off mechanism, guides therefor, an actuator, a pinion mounted thereon, and an idler between the rack and the pinion.

7. In a controlling mechanism, the combination of a variable cut-off mechanism, a rack for moving the cut-off mechanism, guides 60 therefor, an actuator, a pinion mounted thereon, an idler between the rack and the pinion having two sets of teeth, each set having a different pitch diameter, and means for adjusting the rack to certain definite positions.

65 8. In combination, a pair of cut-off mechanisms, a rack for connecting and actuating them, guides for the rack, an actuator, gear-

ing between the rack and the actuator, and a common support for the actuator and the rack-guides.

9. In combination, a cut-off mechanism, a rack for actuating it, guides therefor, an actuator, gearing between the rack and the actuator, and a single support by means of which the guides, gearing and actuator are 75 sustained.

10. In combination, a pair of cut-off mechanisms, a rack for connecting and actuating them, which rack is adjustable with respect thereto, a tubular actuator, a pinion secured 80 thereto, a support for one end of the actuator, extensions formed on the support which act as guides for the rack, means carried by the support for adjusting the cut-off mechanisms to certain definite positions, and an idler between the rack and the pinion which is also carried by the support.

11. In a controlling-stand, the combination of a socket, a stationary tube mounted therein, a movable tube mounted within the stationary tube and guided at its lower end by the socket, a handle for actuating the tube, a bushing or bearing which makes a working fit with the stationary and the movable tube, and a pinion secured to the lower end of the 95 movable tube, the bushing and the pinion acting together to prevent end movements of the actuating-tube independent of the stationary tube.

12. In a controlling mechanism, the combination of an actuator, a rack, a support for the actuator which also has guides for the rack, an arm pivoted to one of the guides for adjusting the rack to certain definite positions, and a spring secured to the other guide 105 for forcing the arm into engagement with the rack.

13. In a vehicle, the combination of a body, a seat, a motor, a controlling-stand situated adjacent to the seat, a guide for the upper end 110 of the stand, a socket for supporting the lower end, a reversing mechanism, means for attaching the reversing mechanism to the socket, a speed-controlling device, and means for operatively connecting the reversing mechanism 115 and the speed-controlling device with the controlling-stand.

14. In a vehicle, the combination of a body, a pair of engines, a separate cut-off and reversing device for each engine, a means for uniting the devices for simultaneous operation, means for adjusting one device independently of the other, and a single handle for simultaneously operating the cut-off and reversing device of both engines.

15. In a controlling mechanism, the combination of a support, an actuator, an eccentric mounted on the actuator, a throttle-valve, a link connection between the valve and the eccentric, and means for holding the eccentric and the valve in proper relation.

16. In a controlling mechanism, the combination of a support, an actuator, an eccentric mounted on the actuator, a throttle-valve,

a link connection between the valve and the eccentric, a bearing for the eccentric, and rods connecting the bearing with the throttle-valve.

5 17. In a vehicle, the combination of a pair of engines, a separate connection from each engine to a driving-wheel, a cut-off mechanism for each engine, means for uniting the cut-off mechanisms, a single handle for simultaneously operating the cut-offs, and a single throttle-valve for controlling the admission of steam to both engines.

10 18. In combination, a pair of separate engines, a separate mechanical connection between each engine and a driving-wheel, a single throttle-valve for controlling both engines, and a separately-actuated cut-out valve for each engine for rendering it inoperative.

15 19. In combination, a pair of separate engines, a separate mechanical connection between each engine and a driving-wheel, a single throttle-valve for controlling both engines, an actuator, and an eccentric and strap connection between the actuator and the valve.

20 20. In a controlling-stand, the combination of a tube, a shaft for actuating the throttle-valve, a head on the shaft which makes a working fit with the tube, an eccentric secured to the lower end of the shaft which is provided with a hub, and a bearing for holding the eccentric in proper alinement with the tube, the head and hub acting to prevent independent vertical movements of the tube and shaft.

25 21. In combination, a pair of levers, with an interlock between the levers, comprising a structure having two parts, one of which moves with one lever and the other part with the second lever, the interlocking members being so arranged that the levers can only be separated when one of them is moved to an abnormal position.

22. In combination, a pair of movable levers, supports therefor and an interlock between the levers which is operative at all times during their normal operation and prevents one of the levers from being detached from its support, but is rendered inoperative when one of them is moved to an abnormal position.

25 23. In combination, a pair of movable levers, one which is capable of working on either the right or left hand side of its support, and an interlock between the levers which is operative when the last-mentioned lever is in the right or left hand position.

24. In combination, a lever capable of moving in one plane, a second lever normally arranged to work in a corresponding plane but pivoted so that it can be swung over from one side of its support to the other, a support for the levers, and an interlock which prevents the removal of one of the levers except when the other lever is in an abnormal position.

60 25. In combination, a tube, a support secured thereto, a handle or lever pivoted to the support, a hooked projection on the lever, a second handle or lever, and a flange thereon with which the hooked projection engages for preventing the removal of the second handle except under certain conditions.

70 26. In combination, a tube, a support clamped thereto, a lever pivotally secured to the support, a pair of hooked projections secured thereto, one of which is always inoperative, and a detachable handle having means engaging with either of the projections for preventing its removal except when the lever is moved to an abnormal position.

75 27. In combination, a pair of levers having the same center of motion and arranged to be separately actuated, a projection carried by one lever, and a second projection carried by the other lever, the two projections being in operative relation to form an interlock when the levers are in their normal operating position and to permit separation of the levers when they are moved to an abnormal position.

80 28. In combination, a controlling-stand, a steering-shaft mounted therein, a lever secured to the shaft, a pair of steering-wheels, means for preventing the transmission of wheel strains, a shaft, a lever connected to the shaft, and a rod connecting the levers mounted on the two shafts.

85 29. In combination, a vertically-extending support, a handle secured thereto, a second vertically-extending support, a handle secured thereto and normally arranged to move in a horizontal plane, and a pivot for the handle arranged at an angle to its normal plane of movement so that the handle can be operatively used on either side of its support.

In witness whereof we have hereunto set our hands this 28th day of January, 1901.

HERMANN LEMP,
OTTO F. PERSSON.
